UNITED STATES PATENT OFFICE.

JOSEPH M. PUSEY, LEA PUSEY, AND EDWARD PUSEY, OF WILMINGTON,
DELAWARE.

IMPROVEMENT IN SPINNING-MACHINES.

Specification forming part of Letters Patent No. 80,216, dated July 21, 1868.

To all whom it may concern:

Be it known that we, JOSEPH M. PUSEY, LEA PUSEY, and EDWARD PUSEY, of Wilmington, in the county of New Castle, and State of Delaware, have invented a new and Improved Ring-Spinning Frame; and we do hereby declare that the following is a full, clear, and exact description thereof, which will enable those skilled in the art to make and use the same, reference being had to the accompanying drawings, forming part of this specification.

This invention relates to new and useful improvements in what are known by cotton-manufacturers as "ring-spinning frames," (having more particular reference to the throstle-frame,) whereby the operation of spinning is greatly improved, both as regards the work performed and the expense attending it; and the invention consists in a device for preventing the spindle from trembling or vibrating when running at a high speed.

Figure 1 represents a vertical section of a throstle-spinning frame with dead-spindles, showing the tube and bobbin on the spindles, and other features which embrace our invention, the section being through the line *x x* of Fig. 2. Fig. 2 is a top or plan view of the same, showing the division-plates between the spindles. Fig. 3 is a vertical sectional view of one side of the frame, showing the parts at full size. Fig. 4 is a horizontal section of Fig. 3 through *y y*. Fig. 5 is a longitudinal section through the line *z z* of Fig. 3.

Similar letters of reference indicate corresponding parts.

A represents the spindle-rail or frame, to which the spindle is secured. B is the spindle. C is the tube around the spindle. D is the bobbin on the tube. E is the ring-rail. F is the angular bar by which the ring-rails E are connected. G represents the spring which we apply to the spindle to prevent jar and vibration when running at a high rate of speed. H is the brake by which the motion of the tube is stopped when it is necessary to mend the thread or for other purposes. I represents the division-plate between the spindles. J is the drum, from which the tubes are revolved by means of the cords K.

The usual method of holding the dead-spindle in the frame is by a set-screw, which of

course confines it rigidly in the frame. For a moderate motion, this method is not particularly objectionable, but in running at a high rate of speed, the jarring and vibration consequent upon the rigid confinement of the spindle by the set-screw interferes more or less to defeat the object in view.

We have found that by giving the spindle (which is loosely placed in its bearings) a certain degree of elasticity by applying to it a slight pressure, by means of a spring or some other elastic substance, we can run at a high speed without jar or vibration. We are thereby enabled to do work which we could not do with spindles rigidly set in the frame in the usual manner.

To accomplish our object we apply the spring G to the spindle, substantially as seen in the drawing. The spring bears against the spindle at two points, as shown in the drawing, and as the spindle is allowed a slight play in its bearings, its tendency to vibrate under a high rate of speed is overcome by the spring. Any movement of the upper end of the spindle would be communicated to the lower end, and cause the spring to yield in a corresponding degree, and prevent the return motion necessary to vibration.

L is an adjustable support to which the spring is attached, and the pressure is regulated by the screws *m* from the frame A.

It will be seen that there is a circular groove in the spindle at *n*, into which one end of the spring sets. This is to prevent the spindle from being raised from its step in the frame.

The ring-rails of the frame are rigidly attached to the ends of the connecting-bar F at each side, and the device for raising and lowering (whether by gearing or other methods) is applied directly to the bar, thereby producing a steady and uniform motion in the rails, and adding greatly to the regularity and completeness of the operation.

The division-plate I is a flat piece of metal, attached to the ring-rail between the spindles at its lower end, and extending up nearly or quite to the top of the bobbin.

As the threads vibrate in consequence of their rapid rotating motion, the plate prevents them from coming in collision, as they not unfrequently do without such a guard between them.

The ring-rail is ordinarily formed with two pendent flanges, *i.* We dispense with one of these flanges, as seen in the drawing, for the purpose of dropping the ring-rail lower down, and at the same time clearing the driving-cord K.

In forming the bobbin, we do not chamber it in boring, as is usually done, but bore it of uniform size from the bottom end to near the top, the upper end being bored to fit the tube, as seen in the drawing. The tube being turned to two different sizes, leaves a chamber between them, as seen, and also enables us to make the tube larger immediately above the grooved pulley, thereby adding to its strength where strength is most needed. This method of boring the bobbin and turning the tube saves the use of an expensive tool for forming the chamber, and greatly simplifies and cheapens the cost of the bobbins. The ordinary method has been to bore the bobbin with a hole of uniform size, and then chamber it out with an expanding tool.

The method of lubricating the spindle is seen at *o*, Figs. 1 and 5. An oil-chamber is drilled into the end of the spindle, into which the lubricating-oil is poured, which oil is discharged through a hole bored laterally to the first, as seen in the drawing. A wick or some fibrous or absorbing material is placed in the hole in the spindle for retaining the oil, and allowing it to be discharged gradually for the required lubrication.

The brake H is attached to the frame, and is in the form of a bent lever, whose fulcrum is at the point P. At the lower end it is connected with a horizontal arm, R.

When the operator desires to stop a bobbin for any purpose, he presses his knee against the arm R, which throws the upper end of the lever or brake H against the tube, causing thereby sufficient friction to stop the motion.

The upper end of the brake, where it comes in contact with the tube, may be provided with rubber or some other elastic substance to prevent abrasion.

In the dead-spindle frame, the tube C runs upon a step marked S, which is usually made of wood.

Being manufacturers ourselves, the improvements which are herein shown and described are the result of careful observation and long experience in the business, and may be considered as an important step in improving and perfecting manufacturing machinery.

Having thus described our invention, we claim as new and desire to secure by Letters Patent—

1. The combination, with the spindle, of the spring bearing on the spindle, to hold and steady the same, substantially as described, for the purpose specified.

2. The combination of the spring G, the connecting-bar F, the adjustable support L, the division-plate I, and the brake H, with a ring-spinning frame, substantially as described.

JOSEPH M. PUSEY.
